AUTOMATIC BOOM LOCK

Floyd Currier, Oakland, Calif.

Application March 8, 1946, Serial No. 653,083

5 Claims. (Cl. 212—58)

1

This invention relates to automatic boom locking devices and more particularly to an automatic boom lock for use on boom masts of cargo ships and the like.

A main object of the invention is to provide a novel and improved device for locking a boom in raised position on its mast when not in use, said device having control means for unlocking the device, said control means being actuated from a remote position such as, from the deck of the ship.

A further object of the invention is to provide an improved remotely controlled boom locking device which is very simple in construction, reliable in operation and easy to control and comprising a small number of easily manufactured parts.

Other objects and advantages of the invention will become apparent from the following description and claims and the accompanying drawings, wherein:

Figure 1 is a top plan view of a boom locking device constructed in accordance with the present invention.

Figure 2 is a cross-sectional view taken on line 2—2 of Figure 1.

Figure 3 is a cross-sectional view taken on line 3—3 of Figure 1.

Figure 4 is a cross-sectional view taken on line 4—4 of Figure 1.

Figure 5 is a perspective detail view of a locking jaw member employed in the boom locking device of Figure 1.

Referring to the drawings, 11 designates a substantially circular base plate which is adapted to be secured to the top of the stationary vertical boom mast. Secured to base plate 11 is a bottom horizontal support member 12 and a top horizontal support member 13, a spacer block 14 being interposed between the rear portions of support members 12 and 13 and all three members being rigidly fastened to base plate 11 by bolts 15. Support members 12 and 13 are similar in shape, member 12 being formed with a pair of apertured forwardly extending arms 16 and 17 and member 13 being formed with a pair of apertured forwardly extending arms 18 and 19, the apertures in arms 16 and 18 being vertically aligned and the apertures in arms 17 and 19 being similarly vertically aligned. Between the forwardly extending arms, members 12 and 13 are concave in contour, as shown at 20.

Pivottally secured by a bolt 21 between arms 17 and 19 is a first jaw member 22 having a rearward body portion 23 of reduced thickness which

2

is disposed adjacent lower support member 12. Pivottally secured between arms 16 and 18 by a bolt 24 is a second jaw member 25 having a rearward body portion 26 of reduced thickness which overlies the rearward body portion 23 of jaw member 22. Rearward body portions 23 and 26 are shaped so that they are substantially flush with concave surface 20 when the jaw members are in locked position as shown in Figure 1.

Secured to the top support member 13 at a rearward position thereon are a pair of angle bracket members 27, 28, between the upstanding arms of which is pivotally secured a lever bar 29. Loosely connected to the forward end of lever bar 29 is a depending pin member 30 formed with an integral collar 31 normally bearing on the top surface of upper support member 13, said pin member 30 being adapted to pass through vertically aligned apertures 32 and 33 formed in the respective support members 13 and 12. The rearward portions of the jaw members 22 and 25 are also apertured to receive the pin member 30, each jaw member having a first aperture for locking it in closed position and a second aperture for locking it in open position, as shown at 34 and 35 respectively in Figure 5. A coil spring 36, contained within a housing 37 provided therefor on upper support member 13, encircles pin member 30 and bears on collar 31, thereby biasing the pin member downwardly with respect to the upper wall of housing 37.

The free end of lever member 29 is connected by a cable 38 to a control station on the deck of the ship.

To unlock the jaw members, cable 38 is pulled downwardly which causes lever arm 29 to rotate on its pivot and raises pin member 30 against the pressure of spring 36 out of engagement with the respective aligned apertures 34 in the rearward portions of the jaw members. This releases the jaw members, allowing them to be swung apart by the boom as it leaves the space adjacent concave surface 20. As the jaw members are swung apart their alternate locking openings 35 come into registry with stationary openings 32 and 33 and pin member 30 may be released to thereby lock the jaw members in open position. When it is desired to lock the boom in its inoperative position the boom is raised until it abuts the rearward portions of the opened jaw members, cable 38 is pulled downwardly to raise pin member 30 and release the jaw members, and the boom is allowed to rotate the jaw members to their locking position, which is shown in Figure 1.

55 In this position the first set of locking apertures

of the rearward portions of the jaw members are in registry with the upper and lower pin apertures 32 and 33 and pin member 30 may be lowered into locking position with respect to the closed jaw members.

While a cable 38 has been shown herein as the actuating means for raising pin member 30, lever bar 29 may be rotated by any other suitable remotely controlled actuating device such as a pneumatic cylinder, an electro-magnet, or the like, in place of cable 38.

To protect the mechanism from the effects of adverse weather conditions a suitable housing of sheet metal or the like may be employed to cover the rearward portion of the device.

While a specific embodiment of a boom locking device has been disclosed in the foregoing description, it will be understood that various modifications within the spirit of the invention may occur to those skilled in the art. Therefore it is intended that no limitations be placed on the invention other than as defined by the scope of the appended claims.

What is claimed is:

1. A boom locking device comprising a first horizontal support member formed with a pair of arms, a second horizontal support member formed with a pair of arms each vertically aligned with one of the arms of the first support member, a spacer block between the rearward portions of the first and second horizontal support members, a first horizontal jaw member pivotally secured between a first vertically opposed pair of arms, a second horizontal jaw member pivotally secured between the second vertically opposed pair of arms, the rearward portions of the jaw members overlapping and being received between the forward portions of the horizontal support members, a pair of vertically aligned apertures in the forward portions of said horizontal support members, apertures formed in the rearward portions of the jaw members adapted to register with the support member apertures when the jaw members are in boom locking position, a lever arm pivotally mounted for rotating in a vertical plane on one of the support members, a pin member connected to said lever arm and slidably received in the aligned apertures, and remotely actuated means for rotating said lever arm.

2. The structure of claim 1, and wherein said pin member is formed with a collar and wherein a stationary abutment is provided on one of the horizontal support members adjacent said pin member, and wherein a spring is provided around said pin member bearing on said collar and on said stationary abutment and positioned so as to bias the pin member towards its aperture-engaging position.

3. The structure of claim 1, and wherein the lever arm is pivoted at an intermediate point thereof and the pin member is connected to one end of said lever arm, and wherein said remotely

actuated means is a cable connected to the other end of said lever arm and arranged so that said lever arm will raise the pin member outwardly with respect to the support member apertures responsive to a pull on the cable.

4. A boom locking device comprising a first horizontal support member adapted to be secured to the top of a boom mast, said first support member being formed with a pair of spaced arms, a second horizontal support member formed with a pair of spaced arms respectively vertically aligned with the arms of said first support member, a spacer block between the rearward portions of the horizontal support members, a first horizontal jaw member pivotally secured between a first pair of vertically opposed arms, a second horizontal jaw member pivotally secured between the second pair of vertically opposed arms, the rearward portions of the jaw members overlapping and being received between the forward portions of the horizontal support members, a pair of vertically aligned apertures formed in the forward portions of said horizontal support members, a first set of apertures formed in the rearward portions of said jaw members adapted to register with the support member apertures when the jaw members are in boom locking position, a second set of apertures formed in the rearward portions of said jaw members adapted to register with the support member apertures when the jaw members are in wide open position, the rearward portions of the jaw members being adapted to be abutted by the boom when the boom is being retracted to locked position whereby said jaw members are urged toward boom locking position, a lever member pivotally mounted for rotation in a vertical plane on said second support member, a pin member connected to one end of said lever member and slidably received in the first set of aligned apertures when the jaw members are in boom-locking position and the second set of aligned apertures when the jaw members are in wide-open position, and remotely actuated means for rotating said lever member to raise said pin member.

5. The structure of claim 4, and wherein said remotely actuated means is a cable connected to the other end of said lever member, said lever member being pivoted at an intermediate point thereon, and wherein spring means is provided which biases said pin member toward its aperture-engaging position.
